UNITED STATES PATENT OFFICE.

ERNEST A. CONAWAY, OF LITTLE ROCK ARKANSAS.

SEAL LATCH.

Application filed May 22, 1926. Serial No. 110,956.

This invention relates generally to latching devices for doors and similar closures, but more particularly to seal latches adapted for use in connection with the sliding doors of 5 railway freight cars and the like.

The invention has for its object the provision of a seal latch whereby the sliding door of a railway freight car may be latched in closed or partially opened position.

10 A further object of the invention is to provide a seal latch whereby two levers are utilized and so joined together by a bell crank lever arrangement pivotally secured to the sliding door of the railway freight car that 15 a powerful fulcrum is secured to force said door into closed position as well as to pry said door away from its closed position, this being accomplished in connection with a keeper firmly affixed to the jamb of the door 20 and with which said levers are adapted to cooperate.

A further object of the invention is to provide a simple and highly efficient seal for effectively sealing the seal latch without the 25 use of a die or other special tool, and which, when sealed, cannot be opened without rupturing or puncturing the seal in a manner such that the mutilation is plainly visible.

With the foregoing and other objects in 30 view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which 35 come within the scope of the claims hereunto appended.

40 Fig. I is a plan view of my improved seal latch with the sliding door in closed position, showing in dotted lines the door in partially opened position.

Fig. II is a plan view similar to Fig. I but 45 with the latching levers detached from the keeper.

Fig. III is a top plan view, partly in section, of my improved seal latch.

50 Fig. IV is a cross-sectional view taken on line IV—IV, Fig. III, showing the keeper and the latching levers in latched position.

Fig. V is a detail front sectional view taken on line V—V, Fig. IV, of the keeper and the latching levers in locked position.

Fig. VI is a cross-sectional view taken on 55 lines VI—VI, Fig. II.

Fig. VII is a perspective view of one of my improved cap seals with flange.

Fig. VIII is a view of another form of cap seal of disk shape. 60

In the drawings my improved latch is shown as comprising a keeper 1, securely attached to a freight car door jamb A, and securing elements 2 and 3. The keeper comprises a cylinder, or barrel, 4 preferably made integral with a base plate 5. The cylinder and base plate may be made of any desired material possessing the requisite strength. Apertures are provided in the base plate 5 for the purpose of securing the plate to the jamb A 70 by means of suitable bolts as shown at 6.

The base plate 5 is provided at one end with a hollow boss 7 having an open vertical side wall 8. As shown in Fig. V, the opening 8 does not extend completely to the top wall of 75 the boss 7, but terminates short thereof. An integral lip 9 of substantial thickness is provided at the bottom of said opening 8 near the cylinder 4, which, together with a projection or lip 10 (see Fig. III), also of substantial 80 proportion, formed on the inside of one of the side walls of said opening 8, serves as a keeper for the lever member 3. The boss 7 is further provided with an aperture 11 which provides a communicating channel between the 85 interior of the cylinder 4 and the interior of the hollow boss 7.

The cylinder 4 is made hollow, as clearly shown in Fig. IV, and the lower portion is cut away to permit the insertion and withdrawal 90 of one end of the lever member 2. The interior wall of the cylinder 4 is formed either at the time of casting the piece or by machine processes later, with an arcuate upper portion 12 (see Fig. V) into which the channel 95 11, communicating with the hollow boss 7, opens as shown most clearly in Fig. V. The arcuate portion 12 of the cylinder merges into substantially straight vertical side walls 13 and 14, which are cut away as at 20 to form 100 shoulders 15 extending from the rear wall 16 of the cylinder parallel to the axis thereof to

a point adjacent to but short of the front wall 17 of the cylinder. Two of the shoulders 15 are provided, one on either side of the axis of the cylinder and slightly above the same.

5 Immediately below each of the shoulders 15 and in the planes of the walls 13 and 14, respectively, lugs 18 are formed (see Fig. VI). The lugs 18 are formed with lower arcuate faces 19 which serve to connect the 10 inner vertical side walls 13 and 14 with the cut-out portions 20 thereof, and in reality form continuations of the shoulders 15 with which they are adapted to functionally co-operate in a manner to be hereinafter described. The forward wall 17 of the cylinder is provided with an axially positioned aperture 21 which provides means for the insertion of an operating tool (not shown) for the purpose of manipulating a latch member 15 carried by the free end of the lever 2.

The levers 2 and 3 hereinbefore referred to are generally of the pivoted hooked-end type and may be formed of any suitable material having the requisite strength. The 25 main lever 2 is provided at its pivot end with a boss 22 to which is secured, preferably integrally, a bell-crank arm 23 which is adapted to pivotally support the lever 3 which is in the plane of the lever 2. To 30 this end a pivot pin 24 is provided in one end of the bell-crank 23 by which the lever 3 is pivotally attached through said bell-crank to the lever 2, which latter lever is pivotally mounted upon a base plate 25 by means of a suitable bolt 26. The base 35 plate 25 is secured to the door B by bolts 25^a. The lever 3 is provided with a hooked end 27, as shown in Fig. II, and a tapered side projection or hook 28 at the same end 40 where the hook 27 is located, as seen in Figs. III and IV. These hooks 27 and 28 are adapted to enter the opening 8 in the side wall of the boss 7 and cooperate with the lip 9 and projection 10 therein provided.

45 The main lever 2 is formed with a hooked end 29 which is tapered on one side toward its end, as seen at 30 in Fig. IV, and is adapted to contact with the tapered face 31 on the hook 28 on the lever 3, as also shown 50 most clearly in Fig. IV.

An open-ended hollow stud or housing 32 is formed on the lever 2 at the end containing the hooks 27 and 28 and the axis of which is substantially perpendicular to the plane of the lever and parallel to the pivotal axis thereof. The wall of the stud or housing 32 is longitudinally slotted at 33, said slots extending from near the outer or projecting free end of the stud at diametrically opposite points inwardly toward the rear of the stud to a point adjacent thereto but short thereof. The slots in the wall of the stud 32 are for the purpose of guiding and confining a pair of pins 34 carried

by and projecting radially from a block or 65 plunger 35 housed within the hollow stud and adapted to reciprocate therein. The block 35 is urged into an extreme outward position by means of a coil spring 36 housed within the stud behind the block, said block 70 being retained within the housing and limited in its forward movement by the end walls of the slots 33 adjacent the forward end of said block 35. It is apparent from this construction that the pins 34 projecting radially 75 from the block 35 through the slots 33 will engage the end walls of the slots which thus determine the range of reciprocation of the block within the stud or housing 32. It is to be noted that the radially projecting pins 80 34 extend beyond the outer wall of the stud a substantial distance, and the purpose of this construction will presently be made apparent.

The sides of the pins 34 adjacent the lugs 85 18 are preferably slightly rounded so as to insure their riding freely over the lugs 18. The outer or free end of the main lever 2 is further provided with a shield or guard 37, preferably of substantially the same diameter as the cylinder 4 and extending forwardly of the plane of the lever 2 a distance corresponding to the depth of the cylinder 4 and extending rearwardly of the plane of the lever a distance corresponding to the 95 thickness of the rear wall of the cylinder 4.

The base plate 25 which is attached to the sliding car door B by means of the bolts 38 is preferably of elongated construction having a central oblong raised portion 39 100 which is provided with an irregularly shaped slot 40 in which the bolt 26 is adapted to fit. When the bolt 26 is in the position shown in Fig. II, the car door B will be pulled tightly against the door jamb A when the 105 levers 2 and 3 are located in the keeper 1. When the bolt 26 is in the other end of the slot 40, as shown in dotted lines in Fig. I, the car door B will be permitted to remain partially open (for ventilating purposes) 110 when the levers 2 and 3 are secured in the keeper.

41 and 42 are lugs formed on the levers 2 and 3 near their free ends, said lugs being outwardly turned and apertured as at 43 115 (see Fig. III) for the purpose of having an additional locking element to engage said lugs if such be desired. 44 is an ordinary grip iron to assist in opening and closing the sliding door B.

In the application of my invention to the sliding door of an ordinary railway freight car, the base plate 25 carrying the levers 2 and 3 is secured to the sliding door B by means of the bolts 38. As shown in Figs. 125 I and II, the pivot pin 26 of the lever 2 is extended only through the raised portion 39 of the base plate 25. The construction of

this base plate is of sufficient strength to insure this bolt or pin 26 being very securely retained in position. The keeper 1 is mounted on the jamb of the door by suitable bolts 5 and 6 and in a position such that when the door B is closed the levers 2 and 3 may be operatively associated therewith, and in the positioning of the pivot pin or bolt 26 shown in dotted lines in Fig. I the door B may be 10 left in a slightly open position for ventilating purposes.

Assuming the invention to have been mounted as just described, the door is latched by first guiding the lever 3 into the opening 8 of the boss 7 as the door B is being moved to its closed position. By virtue of the bell-crank 23 and the spacing of the levers and keeper, the hooked end of the lever 3 being inserted in the keeper and caught by the lip 9, the upward movement of the lever 2 acts as a fulcrum to slide the door B tightly into its closed position when the parts are mounted, as shown in full lines in Fig. I. As just stated, the hooked end 27 of the lever 3 drops 25 behind the lip 9 and is securely retained in said keeper in said lip in the primary instance. When the lever 3 is in the position just described within the keeper 1 the main lever 2 is then brought into the position shown 30 in full lines in Fig. I by swinging the same about its pivot pin 26, so that it may enter the hollow cylinder 4 from below. Upon entering the end of the lever into said cylinder the slightly rounded sides of the projecting pins 34 are carried by the reciprocable block 35 engage the cam surfaces 19 of the lugs 18, and due to the camming action taking place between the lugs and the pins the resistance of the spring 36 is overcome and 35 the block 35 is forced or retracted within the stud 32, thus allowing the end of the lever 2 to move within the hollow cylinder 4. When the pins 34 reach the ends of the cam surfaces 19 of the lugs 18 the end of the lever 2 drops completely within the cylinder 4, the pins 34 engaging the shoulders 15 and being in this position clear of the cam lugs 18, the spring 36 comes into play and forces the block 35 forwardly, thus bringing the pins 50 34 beneath the overhanging portions of the lugs 18. The depending lug 29 carried at the extremity of the downturned end of the lever 2 enters the channel 11 in the top wall of the cylinder and cams against the tapered end of the lever 3, as shown most clearly in Fig. IV, causing the projection 18 to engage the lip 10 and thus securely hold said lever 3 in locked position. It is to be noted 55 that the shoulders 15 within the cylinder 4 are so positioned as to bring the stud 32 into actual alignment with the cylinder 4, the open end of said stud registering with the opening 21 in the front wall of the cylinder 4. It will thus be seen that the lever 3 can only be released by first releasing the main lever 2, and

that the latter can only be released by retracting the bolt 32 sufficiently to allow the pins 34 to clear the overhanging portions of the lugs 18, which may be accomplished by introducing a suitable instrument into the keeper through the opening 21 thereof.

In order to prevent an unauthorized opening of the latch, or to prevent its being opened and relocked without visible evidence thereof, a seal 45 is provided preferably in the form of a sheet metal cup-shaped disk which, as shown in Fig. VII, may be embossed or otherwise provided with the name or initials of the railroad company. This seal is provided with a lip 46 apertured as shown, whereby the seals may be serially numbered and threaded on a wire or other suitable device so that they may be removed and used in consecutive serial numbers. A disk seal 47 may be employed instead of the cup-shaped seal 45, which disk seal is provided with ears 48 having downturned projections 49 by which this form of seal may be attached to the bolt 32. This disk seal 47 may also be embossed as shown and likewise be threaded upon a wire or other suitable device, in serially numbered relationship, through the apertures formed when the projections 49 are stamped out, and said seals 47 may likewise be employed in their respectively serially numbered rotation. Either type of seal, prior to the closing or locking of the main lever 2, is fitted over the forward open end of the stud or housing 32 (see Fig. IV), it being apparent that sufficient clearance is provided between the end of the stud 32 and the inner face of the front wall 17 of the cylinder 4 to permit the lever 2 to be then snapped into place as above described. When the lever 2 is in its latched position and firmly seated within the keeper 1, the shield or guard 37 carried by said lever functions to completely close the lower part of the keeper, as clearly shown in Figs. I, IV and V. It is therefore apparent that the cylinder 4, the guard 37 and the seal 45 (or 47) completely enclose the locking mechanism of the lever 2, which lever must, from the construction of the device, be released before either the lever 3 or the door B of the car may be opened. The levers, keeper, cylinder and guard being of heavy and rugged construction and the latching mechanism being completely enclosed thereby, the only means of opening the latch without entirely destroying the same is by way of the opening 21 in the front wall of the cylinder 4, and this, as hereinbefore set forth, is obstructed by a seal of the type like that shown in either Fig. VII or Fig. VIII.

The block 35 and spring 36 are retained in position in the hollow stud 32 by the plate 50, which is securely retained in position by the screws 51. 53 is a handle to facilitate the operation of the lever 2.

In view of this fact the front face of the cylinder immediately surrounding the opening 21 is beveled as at 21^a so that the seal disk, which is preferably made of bright sheet metal of non-rustible character, will be plainly visible and in striking contrast to the dark cast or forged metal of the latch cylinder. By this construction the least mark or evidence of tampering with the latch is plainly visible, thus rendering a minute or careful examination unnecessary to discover an unauthorized attempt to open the car.

As hereinbefore stated, the lever 2 having been snapped into position within the keeper 1 with a seal disk mounted upon the outer end of the stud 32, the only means of opening the latch is by way of the opening 21 in the disk seal. To this end the disk seal is made of tough but relatively thin, penetrable sheet metal and the members of the train crew and other persons authorized to open the cars are provided with sharp pointed instruments whereby the metal of the disk may be penetrated, the block 35 depressed or retracted sufficiently to move the pins 34 clear of the lugs 18, and the latch then opened in a manner obvious from the previous description. If desired the usual switch keys carried by the train crew may be provided with a sharpened extremity, or any other suitable instrument capable of being used for this purpose may be employed if desired.

When it is desired to open the sliding freight car door B the lever 2 is released as above described, and when it is moved downwardly it acts through the bolt 26 and the bell-crank arm 23 to exert a powerful leverage through the lever 3 against the keeper 1 and thereby forces the car door open several inches.

From the foregoing description it is apparent that the levers having been snapped into place and sealed either of the levers may be broken between the keeper and their pivot pins without releasing the other or allowing the door to be opened. Furthermore, while the lever 3 is merely a pivoted hooked end lever with no means of itself to perform a locking function, the lever 2 and the keeper 1 common to both levers are so formed that when the levers are in position within the keeper the tapered lug 29 carried by the lever 2 engages the tapered hooked end 28 of the lever 3, locking said hooked end 28 behind the lip 10, thus rendering the release of the lever 3 impossible until the main lever is released, yet the construction employed is such that either of the levers may be used separately and independently of the other if desired. It is also to be noted that by providing the cylinder with an arcuate bottom and the bolt 2 with a cylindrical stud or housing 32 adapted to cooperate with the arcuate bottom, means is provided which allows a wide range of relative movement of the car parts with

which the latch is associated without interfering with the operation of the same.

I claim:

1. In a device of the character described, a keeper, two levers adapted to engage said keeper, a support for said levers attached to a sliding freight car door, said support comprising a base plate provided with means whereby said levers may be pivotally supported at different points on said base plate, substantially as described. 75

2. In a device of the character described, a keeper, two levers adapted to engage said keeper, a support for said levers attached to a sliding freight car door, said support comprising a base plate provided with a slot whereby said levers may be pivotally supported upon said base plate at different points in said slot, substantially as described. 80

3. In a device of the character described, a keeper, two levers adapted to engage said keeper, a support for said levers attached to a sliding freight car door, said support comprising a base plate provided with an irregularly shaped slot whereby said levers 90 may be pivotally supported upon said base plate at different points in said slot, substantially as described. 95

4. In a device of the character described, a keeper, two levers adapted to engage said keeper, one of said levers being provided with an inclined projection at its free end adapted to engage an inclined projection on the free end of the other of said levers when said levers are engaged with said keeper, and a pivoted support for said levers, substantially as described. 100

5. In a device of the character described, a keeper, two levers adapted to engage said keeper, one of said levers being provided 105 with a projection at its free end adapted to engage a lip in said keeper, and another projection having an inclined surface also at the free end of said lever, the last named projection being adapted to be engaged by an inclined projection on the free end of the other of said levers when said levers are engaged with said keeper, and a pivoted support for said levers, substantially as described. 110

6. In a device of the character described, a keeper, two levers adapted to engage said keeper, one of said levers being provided with a projection at its free end adapted to engage a lip in said keeper, and another projection having an inclined surface also at the free end of said lever, said projection being adapted to engage another lip in said keeper, an inclined projection at the free end of the other of said levers adapted to 120 engage with the inclined face on the last named projection of the first named lever when said levers are engaged with said keeper to retain the first named lever in locked position in said keeper, and a pivoted 125 support for said levers, substantially as described. 130

support for said levers, substantially as described.

7. In a device of the character described, a keeper, two levers adapted to lockingly engage said keeper, a lug intermediate the free end of each of said levers, each lug being provided with an aperture for receiving an

additional locking device for retaining said levers in locked position, and a pivoted support for said levers, substantially as described. ¹⁰

In testimony that I claim the foregoing I hereunto affix my signature.

ERNEST A. CONAWAY.
